CLAIM

The ornamental design for a camera hub, as shown and described.

DESCRIPTION

FIG. 1 is a top front perspective view of a camera hub in accordance with the present invention;
FIG. 2 is a front plan view thereof;
FIG. 3 is a back plan view thereof;
FIG. 4 is a top elevation view thereof;
FIG. 5 is a bottom elevation view thereof;
FIG. 6 is a right side elevation view thereof;
FIG. 7 is a left side elevation view thereof;
FIG. 8 is a bottom front perspective view thereof;
FIG. 9 is a bottom back perspective view thereof;
FIG. 10 is a top back perspective view thereof; and,
FIG. 11 is an alternative top front perspective view thereof. The broken lines shown in the drawings depict portions of the camera hub that form no part of the claimed design.
